CARRIER RACK FOR VEHICLES OR SIMILAR ARTICLE

Kenneth W. Binding, Medford, Mass., assignor to
Market Forge Company, Everett, Mass., a cor-
poration of Massachusetts

Application February 6, 1953, Serial No. 23,475

Term of patent 14 years

(Cl. D14—6)

To all whom it may concern:

Be it known that I, Kenneth W. Binding, a citizen of the United States of America, residing at 830 Fellsway, Medford, Massachusetts, have invented a new, original, and ornamental Design for a Carrier Rack for Vehicles or Similar Article, of which the following is a specification, reference being had to the accompanying drawings, forming a part thereof, and wherein

Fig. 1 is an isometric view of a carrier rack for vehicles or similar article showing my new design;

Fig. 2 is a side elevational view; and

Fig. 3 is a bottom plan view of the full line portion of Fig. 1.

The dominant feature of my design resides in the full line portion of the drawing.

I claim:

The ornamental design for a carrier rack for vehicles or similar article, substantially as shown and described.
